Thomas H. Doherty, South Bend, Ind., assignor to
United States Rubber Company, New York,
N. Y., a corporation of New Jersey

Application February 6, 1953, Serial No. 23,472

Term of patent 14 years

(Cl. D7—4)

To all whom it may concern:

Be it known that I, Thomas H. Doherty, a citizen of the United States, residing at South Bend, in the county of St. Joseph and State of Indiana, have invented a new, original, and ornamental Design for an Overshoe or Similar Article, of which the following is a specification, reference being had to the accompanying drawing, forming part thereof.

Fig. 1 is a side elevational view of the overshoe or similar article with the flap closed.

Fig. 2 is an elevational view of the opposite side of the overshoe or similar article.

Fig. 3 is a front perspective view thereof illustrating the flap in an open position.

I claim:

The ornamental design for an overshoe or similar article, as shown.
